ABSTRACT OF THE DISCLOSURE

A projectile launcher comprises a fixed percussion device having a cylindrical recess at its forward end and a launcher having a cylindrical outer contour at its rear end which freely but closely slidably fits within the percussion device recess. The launcher has an internal explosion chamber for receiving an explosive charge. A projectile has a cylindrical recess at its rear end that freely but closely slidably fits over the cylindrical forward end of the launcher, so that the side walls of the percussion device recess and the projectile recess between them confine and reinforce at least most of the side walls of the explosion chamber. The explosion chamber has a slidable piston therein so that it is expandable at the same time that it is tightly closed, so that noise and gas do not escape.

The present invention has for its object an engine launching device, such as anti-tank grenades, tear-exciting grenades, bursting grenades, firing grenades, and so on, by means of a launching charge located in an explosion chamber.

There now exist different categories of launching devices of this type which are the following:

(1) The launching devices in which the propulsive charge is fast with the gun-carrier or resting and sighting device. The major drawback of these devices resides in the impossibility to effect rapid firing. In fact, between each firing, one has to load the launching device, which necessitates obviously a loss of time.

(2) The launching devices in which the propulsive charge is fast with the grenade or engine having to be launched. The major drawback of this type of propulsion device is to increase, nearly to double, the weight of the grenade for a same useful charge of it, which causes naturally a great reduction of the range as well as a great increase of the recoil of the launching device for a given propulsive charge.

The two types of launching devices mentioned hereabove may have either a closed explosion chamber, or an explosion chamber communicating with an expansion and escape chamber for the explosion gases. However, the first solution, with the closed explosion chamber, is generally preferred even though it requires a stronger and thus heavier explosion chamber, since it permits to obtain an operation of the launching device which is perfectly silent.

The present invention has for its object a launching device for a projectile, comprising a gun-carrier provided with a percussion and detent device as well as a launching charge located inside an explosion chamber char-

2

acterized by the fact that this explosion chamber is connected to the projectile and/or to the percussion and detent device by means of a sliding coupling in the axial direction and by the fact that the launching charge is independent as well from the projectile as from the gun-carrier and of its percussion and detent device, so that after firing this launching charge is ejected but still not launched with the projectile.

The attached drawing shows schematically and by way of example one embodiment and some variants of the launching device for engines according to the invention.

FIGURE 1 is a partial longitudinal cross-section of the launching device showing more particularly the launcher in firing position.

FIGURE 2 is a partial longitudinal cross-section of the launcher showing a variant of it.

FIGURE 3 is a partial longitudinal cross-section of the launching device showing more particularly the percussion and detent device at the unloaded stage.

FIGURE 4 is a longitudinal cross-section of the percussion and detent device during its loading.

FIGURE 5 is a partial longitudinal cross-section of the launching device showing more particularly the launcher immediately after the firing.

FIGURE 6 is a view on a reduced scale, certain parts being partially broken away, of the launching device provided with a projectile in firing position.

FIGURE 7 is a partial view on a reduced scale, certain parts being broken away, of the launching device and of the projectile immediately after the firing.

FIGURE 8 is a partial view on a reduced scale of one embodiment of the launching device comprising an orientable gun-carrier.

FIGURE 9 shows a variant of the launching device this one being mounted on a fire-arm.

FIGURE 10 shows a variant of the launching device which comprises a fixed gun-carrier.

FIGURE 11 shows a variant of the launching device on a rifle butt.

FIGURE 12 shows a variant of the launcher in partial longitudinal cross-section.

The launching device, object of the present invention, comprises a gun-carrier or resting and sighting device, a launcher or explosion chamber, provided with its launching charge and a percussion and detent device, fixed on the gun-carrier, the whole being provided for the launching of an engine, such as an anti-tank grenade, a tear-exciting grenade, an explosive charge grenade, a firing grenade, or a signalisation grenade and so on.

The gun-carrier A may present different embodiments as illustrated in FIGURES 8 to 11 but it always serves as a support during the firing as well as a sighting device.

In the variant shown in FIGURE 8, the gun-carrier A is constituted by a base plate 1 the lower surface of which comprises formations 2 intended to enter in contact with the ground and to provide a good support enabling the absorption of recoil. The upper surface of this plate is for example planar and comprises a threaded blind hole intended to receive the threaded lower end of the percussion and detent device B. A sighting member 3 is also fixed on the upper surface of the plate 1.

The gun-carrier forms a mobile support which can be

orientated. In fact the rifleman lays the base plate 1 on the ground and orients it in the desired direction. Thanks to the formations 2 of the lower face of this base plate 1, it is able to transmit the recoil of the firing to the ground even if this plate 1 forms with the surface of the ground a pronounced angle.

In the variant shown in FIGURE 10, the gun-carrier A is constituted by a plate 4 the surface of which is adapted to receive the percussion and detent device B as well as the sighting member 3 as in the variant shown at FIGURE 8. But the lower face of this plate 4 is provided with a point 5 intended to be driven in the ground. This variant constitutes thus a gun-carrier enabling firing several times successively without proceeding to a new sighting operation. In fact the orientation of the plate 4 and thus of the gun-carrier is fixed.

In the variant shown in FIGURE 9, the gun-carrier of resting and sighting device A constituted by the plates 1 and 4 of the variants of the gun-carrier shown at FIGURES 8 and 10 is replaced by a sleeve 6 on one end of which the percussion and detent device B is threaded whereas its other end presents a blind hole enabling this sleeve to be slid over the free end 7 of a gun for example.

Finally, in the variant shown in FIGURE 11, the sleeve 6 described in reference to FIGURE 9 is fixed by means of fixing members 8 on a butt 9. This butt 9 constituting the gun-carrier A is provided with damping members 10 and 11 of synthetic or natural rubber for example in order to damp the recoil effect during the firing. This last variant of the gun-carrier for the propulsion device is particularly well adapted to short-range firing.

The percussion and detent device B is fastened by its lower threaded end 12 on the gun-carrier A so as to be solid with it but still removable. In this way a same percussion and detent device B may be used according to the needs with anyone of the types of gun-carriers described above or of the existing gun-carriers.

This percussion and detent device comprises a support 13 the lower threaded extremity 12 of which (FIGURE 4) is fixed to the gun-carrier A and the upper part of which forms a chamber 15 the upper front end of which is open and gives passage to the lower part 16 of a sliding member 17 of this device B. This lower part 16 of the said sliding member 17 presents an outside diameter which corresponds to the diameter of the chamber 15 of the support 13 and a length which is equal to that of the chamber 15. This sliding member 17 slides without clearance inside the chamber of the support 13. The upper part 18 of this sliding member 17 presents a diameter which is greater at its lower part so as to form a shoulder 19 limiting the depth of introduction of the lower part 16 in the chamber 15 of the support 13.

The bottom 20 of the lower part 16 of this sliding member is pierced by a hole 21 opening inside a first housing of small diameter 22 giving access itself to a second housing 23 of greater diameter and extending inside the greater part of the sliding member 17. This second housing 23 is limited upwardly by a wall 24 driven in the bottom of a hole 25 opening in the upper front face of the sliding member 17.

This wall 24 is pierced in its center and gives passage to a percussion pusher 26 the head 27 of which is located inside the hole 25 and is of greater diameter than the hole in the wall 24 whereas its tail traversing the said wall is provided with a piston 28 the diameter of which corresponds to that of the second housing 23 provided inside the sliding member 17. The length of the tail of the percussion pusher 26 is such that this pusher may effect axial displacements along the longitudinal axis of the percussion and detent device of the order of 2 to 7 mm. for example.

A stopping rod 14 fixed rigidly to the support 13 and extending axially through the chamber 15 traverses the hole 21 of the sliding member 17 and extends coaxially inside the housings 22 and 23 of the lower part of this sliding member 17. The length of this stopping rod 14 is

approximately equal to the sum of the lengths of the chamber 15 and of the part of the second housing 23 located inside the lower part 16 of the sliding member 17. The upper end of this stopping rod 14 presents an abutment 29 constituted in the example shown by a nut threaded on the upper threaded end of this stopping rod 14.

A sleeve 30 slides freely inside the second housing 23 and presents a height approximately equal to the length of the part of this housing 22 located inside the lower part 16 of the sliding member 17. The outside diameter of this sleeve 30 corresponds to the diameter of the second housing 23 whereas the inside surface of said sleeve 30 comprises an annular stop 31 the upper face of which is intended to cooperate, during the loading of the percussion and detent device, with the lower face of the abutment 29 of the stopping rod 14 which extends through this sleeve 30. A spring 32 resting on the bottom 20 of the sliding member 17 on the one hand and on the lower face of the annular stop 31 of the sleeve 30 on the other hand tends to maintain this sleeve in a position such that its annular stop 31 is driven against the abutment 29 of the stopping rod 14.

Finally, the percussion and detent device B comprises further a detent pivoted on the sliding member 17 and comprising a retaining finger 33 which, in loaded position, extends into the housing 23a sufficient distance, defined by a dog 34 cooperating with the outside surface of the upper part 18 of the sliding member 17, in order to be located on the path of the sleeve 30. This detent comprises further a control member 35 and is subjected to the action of a spring 36 tending to maintain it in loaded position.

It is further to be noted that the outside diameter of the support 13 is equal to the outside diameter of the upper part 18 of the sliding member 17 so that when the percussion and detent device is either in loaded or in unloaded position the outside surface of this device B is smooth and does not present any projection other than the detent 32 itself. This is important for the security of the rifleman, who does not risk in any case being hurt by the recoil of the propulsion device at the time of the firing.

The working of the percussion and detent device is the following:

In unloaded position, illustrated in FIGURE 3, the sliding member 17 is completely engaged in the chamber 15 of the support 13 and the sleeve 30 is maintained by its return spring 32 in a high position that is nearly completely located inside the upper part 18 of the sliding member 17. The spring 32 is not compressed in the example shown and the annual abutment 31 does not enter in contact with the abutment 29. However, in a variant the spring 32 could be pre-compressed and the axial position of the sleeve 30 would be determined by the cooperation of the annual abutment 31 with the abutment 29. In this unloaded position, the finger 33 of the detent is maintained against the outside surface of the sleeve 30 under the action of the return spring 36.

To load the percussion and detent device the user displaces the sliding member 17 in the direction of the arrow f (FIGURE 4) until the annual abutment 31 of the sleeve enters in contact with the abutment 29 and the spring 32 is sufficiently compressed and the upper edge of the said sleeve 30 moves under the finger 33 of the detent. This detent moves immediately angularly under the action of the spring 36 so that the finger 33 is disposed in the path of the upper edge of the sleeve 30. The angular displacement of the detent is limited by contact of the dog 34 with the outside surface of the sliding member 17. The displacement of the sliding member 17 in the direction of the arrow f is limited by the cooperation of the lower end of the sleeve 30 with the shoulder separating the first housing 22 from the second housing 23 of this member 17. The respective dimensions of the rod 14, of the sleeve 30 and of the lower part 16 of the member 17

are such that at the end of the stroke the lower part 16 of the member 17 is still engaged in the chamber 15 of the support on a distance sufficient to ensure the guiding.

Then the user displaces the sliding member 17 in the opposite direction to the arrow *f* to replace it in the position which it was occupying before, that is, the position shown in FIGURE 3. During this displacement the sleeve 30 is driven through the finger 33 of the detent against the action of the spring 32 until it reaches its lower position inside the second housing 23, which is itself disposed inside the chamber 15 of the support 13. From that moment, the percussion and detent device B is loaded and it suffices, to cause the firing, to displace the control member 35 of the detent against the action of the spring 36 to free the sleeve 30 which displaces itself under the action of the spring 32 and comes in contact with the piston 28 causing the axial displacement of the percussion pusher 26 which causes then the firing of the launcher in a manner which will be described later on.

The launching device comprises further a launcher C comprising an expansible explosion chamber, in the example shown, as well as a pushing device cooperating with the engine D to be launched and which may be constituted by a grenade of any known type.

This engine D comprises a head 37 housing an explosive charge or a charge of any other nature and a tail 38 provided with guiding flyers 39. The tail 38 is hollowed and presents a cylindrical housing 40. It is to be noted that these engines are of standard dimensions in respect of their tail in any case and that different heads 37 may be adapted to a same type of tail 38.

It is further to be noted that the diameter of the hole 25 opening on the frontal free face of the percussion and detent device presents a diameter identical to that of the cylindrical housing 40 provided in the tail of the engine to be launched.

The launcher C has the shape of a cylinder having a circular cross-section and an outside diameter corresponding to the inside diameter of the hole 25 as well as to that of the cylindrical housing 40. In firing position, shown for example in FIGURES 1, 3, 6 and 10, the lower end of the launcher C is located in the hole 25, whereas its upper end is located in the cylindrical housing 40 of the engine D. This launcher C is thus connected on the one hand to the projectile and on the other hand to the percussion and detent device by means of axially sliding couplings. The outside diameter of the launcher C is such that it slides freely, still being strictly guided, inside the hole 25 and the housing 40.

The lower part of the launcher C comprises a firing chamber 41 the diameter of which corresponds to that of a bullet or blank cartridge of a cartridge case 42 containing launching charge. This firing chamber 41 comprises a hole 43 connecting it to the outside of the launcher in traversing the lower bottom of it. The diameter of this hole 43 corresponds to the diameter of the head 27 of the percussion pusher 26, which in firing position, is located in the said hole and enters in contact with a percussion mass 44 the diameter of which corresponds to that of the firing chamber 41. This percussion mass 44 presents on its face directed towards the cartridge case 42 a percussion projection 45.

The firing chamber 41 intended to receive the cartridge case 42 opens in an explosion chamber 46 presenting a diameter greater than that of the firing chamber 41. These chambers 41 and 46 are separated by means of a piston 47 the skirt 48 of which is intended to surround either the bottom of the cartridge case 42 (variant shown in FIGURE 1), or the bullet 49 or the summit of a blank cartridge case 42 (variant shown in FIGURE 3) depending on whether the cartridge case 42 is placed in the firing chamber 41 in one direction or in the other. The lower free part of this skirt 48 of the piston 47 rests on the shoulder 50 separating the firing chamber 41 from the explosion chamber 46.

The lower surface of the piston 47, located inside its skirt 48, is provided with a percussion projection 51, whereas the frontal upper face of the piston 47 presents a general tapered shape.

According to the position of the cartridge case 42 inside the firing chamber, bottom upwards or bottom downwards, the percussion is obtained by the introduction of the percussion projection 51 or 45 in the frontal face of the bottom of the cartridge case 42.

It is to be noted that the distance separating the two percussion projections 51 and 45, when the percussion mass 44 rests on the bottom of the firing chamber 41 and the lower edge of the skirt 48 of the piston 47 rests on the shoulder 50, is greater than the length of a blank or bullet cartridge case 42, so that any unwanted displacement of the piston 47 can in no case cause the percussion and thus the firing. One should note also that the mass 44 being of very light weight and being able to move a very short way only, it can in no case, even under the action of violent shocks to which the launcher C could be subjected, cause the percussion of the cartridge case 42 and the firing of the launching explosive charge.

In the embodiment shown in FIGURE 1, the upper end of the launcher C is obturated by means of a threaded plug 52 pierced by a hole 53 coaxial with the launcher C. The diameter of this hole 53 corresponds to the diameter of a pushing rod 54, the lower end of which presents a tapered chamfer intended to receive the upper surface of the piston 47, whereas the upper end emerges slightly outside the launcher through the plug 52 and presents a frontal tapered surface cooperating with the bottom of a blind hole provided in a pushing member 55 the frontal surface of which rests against the bottom 56 of the tail of the engine D whereas its diameter corresponds to that of the cylindrical housing 40 of this tail. This pushing member 55 is intended to avoid that the pushing rod 54 penetrate the engine D during the firing.

In the embodiment described, the launcher is reloadable; it suffices in fact after the firing to unscrew the plug 52 which is threaded and to replace the charge. However, in other embodiments, the plug 52 could be driven in under heat or not in the body of the launcher which, in that case, could not be reloaded.

In another variant shown in FIGURE 12, the plug 52 is omitted, in this manner the explosive charge, the piston and the rod are ejected out of the launcher during the firing, even so these parts are independent from the projectile to be launched. In this case the launching device is no more silent, the explosion and expansible chamber being no more closed, but on the other hand the reloading of the launcher is extremely rapidly effected. In certain variants the piston could form itself the projectile to be launched.

It is to be noted that in this variant, the cartridge case is completely housed inside the piston. This piston may in a variant be solid with the pushing rod 54 which is then connected through a sliding coupling to the projectile.

In a variant shown in FIGURE 2, the cartridge case 42 comprises a special bottom 57, which constitutes directly the piston separating the firing chamber 41 from the explosion chamber 46. This bottom 57 comprises a thick wall the diameter of which corresponds to that of the explosion chamber 46 and the lower part of which cooperates with the shoulder 50 separating the chambers 41 and 46. In this variant, the percussion projection 51 is carried by the lower frontal face of the pushing rod 54. A washer 58 of a supple material can be interposed between the frontal face of the bottom 57 and the percussion projection 51 to avoid any unwanted firing.

The operation of the engines launching device is the following:

When the device is in firing position, that is to say that the percussion and detent device B is fixed on the gun-carrier A, that the launcher C is introduced in the hole 25 of the percussion and detent device and that the tail 38 of

the engine D is slid on the upper part of the launcher, the user proceeds in the above described manner, to the loading of the percussion and detent device B, through a reciprocal movement of the sliding member 17.

Then, when the sighting is effected and the launching device is placed according to the desired orientation, the user causes the firing by displacing the control member 35 of the detent against the action of the return spring 36. This has for effect to withdraw the finger 33 of the detent out of the way of the sleeve 30, which, from then on, displaces itself under the action of its spring 32 in the direction of the piston 28 of the percussion pusher 26. When this sleeve 30, thrown very quickly under the action of the spring 32, reaches the piston 28, it causes a rapid and vigorous displacement of the percussion pusher in the direction of the launcher C. The head 27 of the percussion pusher 26, which is engaged in the hole 43 provided in the lower bottom of the launcher, causes an axial displacement of the percussion mass 44, reducing thus the distance existing between the two percussion projections 45 and 51. The cartridge case 42 containing the explosive charge as well as the piston 47, or, in certain cases, the special bottom 57 of the said cartridge case, are maintained in their location under the action of the weight of the engine D so that the firing can be effected under the action of the axial displacement of the percussion pusher 26. The explosive charge of the cartridge case 42 is thus fired, which causes an explosion. Gases liberated by this explosion push violently the piston 47 or the bottom 57 towards the upper extremity of the explosion chamber 46. This piston 47 drives thus in its displacement the pushing rod 54 as well as the pushing member 55 and through their intermediary, the engine D.

The explosion is effected in a closed chamber and is extremely violent and the engine is launched at initial speeds very high, which permits the obtention of great ranges.

It is to be noted that the launching itself of the engine D causes the ejection of the launcher C from the housing 40 of the tail 38 of the engine, due to the ejection of the pushing rod 54 from the launcher.

One obtains thus the launching of the useful charge only, that is to say of the engine D. The only dead weight which is accelerated is that of the pushing device partially housed inside the launcher and formed by the pushing rod 54 and by the pushing member 55 which, according to the clearance between this pushing member 55 and the housing 40 of the engine D, falls down to the bottom or on the contrary is taken with, through suction effect, the engine D a short distance before falling. The launcher C itself and thus the launching charge is in no case taken with the engine in its trajectory. This particularity enables to considerably lighten the engines to be launched, by reducing their dead weight, which is very important since it enables to reach firing distances which have never been reached with this type of arm, and further to reduce the time between consecutive launchings.

For example, one can say that a useful charge, that is an engine D of a weight of 570 grammes, may be launched, by firing at 45°, a distance of 635 meters by means of a launching charge of the order of 1.6 grammes of powder, that is to say with a normal American cartridge No. 223. The same projectile launched conventionally, for example by a gun with the same charge, reaches a distance of 240 meters only by firing at 45°. With the described device, one obtains in the described test an initial speed of the engine D of the order of 90 meters per second.

Tests have also been made with launching charges of 3.2 grammes of powder, that is with cartridges of the NATO, and, always for a firing at 45° and a grenade of a weight of 570 grammes, a distance of 1100 meters has been reached.

Several other tests have been realized with grenades for cannons of 60 mm. having a weight of 1350 grammes.

The ranges reached are of 600 meters to 1000 meters according to the explosive charge used.

Another advantage of the described device resides in the firing speed. As a matter of fact, the launcher C being simply placed on the percussion and detent device, it is extremely quickly taken out and replaced or ejected during the firing, so as to be ready to receive a new charge.

In certain cases, as illustrated in FIGURES 5 and 7, the launcher C is even automatically ejected by the inertia effect of the piston 47 arriving at the end of its stroke and/or by the suction effect during the ejection of the launcher C from the tail 38 of the engine to be launched. In the firing tests reported above, the automatic ejection of the launcher C has been obtained consistently. It suffices thus to the rifleman, to place a new launcher, onto which an engine has been previously slid, on the percussion and detent device B and to reload it in order to be able to effect a new firing.

In a variant, the launcher could present an upper opening of a diameter equal to that of the explosion chamber 46. In this variant, the launcher is used as a conventional gun with the advantage that the launching charge 42 is ejected at the firing which enables a rapid and even instantaneous reloading of the launcher C. In this case, the launcher remains on the gun-carrier.

It is further to be noted that the loading of the percussion and detent device B is extremely rapid since it requires only a simple reciprocal movement. On the other hand, when the user is trained, or if a special device is provided to this end, he may release the detent sufficiently rapidly in order to obtain an automatic reloading of the percussion and detent device B. As a matter of fact, under the effect of the explosion of the launching charge, the percussion pusher is violently rejected backwards, which causes the violent recoil of the sleeve 30 against the action of its spring 32. If now the detent is released in time, thus subjected to the action of its return spring 36, that is before the sleeve reaches its extreme backward position, it comes to lock itself in loaded position under the finger 33 of the detent. This enables to further accelerate the firing, which may be of the greatest importance.

It is further to be noted that in the variants shown in FIGURES 1, 2 and 5 in which the bottom of the cartridge case 42 is either driven in the piston 47, or this bottom and this cartridge case constitute themselves the piston, one obtains an extremely good closure of the explosion chamber, even though the launcher C is open at both its ends. As a matter of fact, during the explosion, the lower end of the launcher is hermetically obturated by the pushing of the mass 44 against the lower bottom of the launcher, which closes the hole 43. This obturation is absolutely tight, since during tests, no gas escape has been seen at this extremity of the launcher C. Further, due to the extremely violent push inside the cartridge case 42, it has the tendency of dilating and causes a correspondent deformation of the skirt 48 of the piston 47 or of its bottom 57. This radial deformation enables the obtention of a perfect closure of the explosion chamber towards the fore end of the launcher, at the same time that it is also open at its fore end. In the variant shown in FIGURE 3 where the bullet or the front part of the cartridge case 42 is placed in the piston 47, the tightness is slightly less since the skirt of the piston 47 is not driven with force against the internal wall of the explosion chamber 46. Tests have however shown that the tightness was good enough in this case too.

The obtention of a good closure is of first importance, since it permits to realize a silent arm which is not detectable through the escaping gases. In fact, an explosion in the closed chamber is not visible nor audible. This is obviously of great tactical and psychological importance for the use of this arm. Tests made have shown that 24 hours after the firing, the explosion gases were still retained inside the explosion chamber.

In a variant not shown, one can provide for an addi-

tional charge in order to increase the range of the engine to be launched.

This additional charge can be placed between the bottom 56 of the engine D and the pushing member 55, the frontal face of which would present in such a variant a percussion projection. During the firing of the charge contained in the launcher, the axial displacement of the pushing rod 54 and of the pushing member 55 causes the percussion and the firing of the additional charge. Thanks to the adjunction of this additional charge, it is possible, without modification of the launching device, to increase its efficiency 20 to 40%. It is however to be noted that in this case, the arm is no longer absolutely silent, since this additional charge explodes in an open chamber, which is the cylindrical housing 40 of the tail 38 of the engine D.

In a variant not illustrated, the pushing rod 54 could be fast with the pushing member 55 and this assembly could be either taken with the engine D during its launching or maintained with the launcher C.

In another variant, the pushing rod could be realized by a staggering of washers or of parts of low dimensions. In other variants, this rod could be constituted by a tube or even by a liquid column.

In a variant of the launcher where it comprises an upper aperture of a diameter equal to that of the explosion chamber 46, the piston 47 could be fast with the rod 54. It is even possible to give the lower extremity of this rod 54 a shape enabling to realize the function of the piston 47.

In another variant, always in the case where the launcher C comprises a top opening of a diameter equal to that of the explosion chamber 46, the lower end of the rod 54 could be made in a manner to constitute the bottom 57 of the cartridge case 42 containing the launching charge. Such a variant enables an instantaneous reloading of the launcher, in fact after the firing, it suffices to introduce in this launcher a new rod 54 the lower end of which contains the launching charge and constitutes simultaneously a piston. This reloading operation can be effected during the setting in place of a new engine to be launched if the rod 54 is fixed to this engine. This variant is particularly advantageous, since it permits a greater efficiency due to the fact that the rod, fixed to the engine, is directly or indirectly in contact with the propulsive charge.

However, here also the launching charge is connected to the engine on the one hand and to the gun-carrier on the other hand by means of sliding couplings and the automatic separation of this launching charge from the engine and the gun-carrier is obtained during the firing.

In a non-illustrated variant the percussion and detent device could be differently constituted if it permits the firing. Particularly, the percussion could be initiated by the impact of a projectile for example by a gun-bullet in the case where the launching device would be fixed on the end of a gun, the recoil reaction of the launching charge absorbing the kinetic energy of the bullet.

This percussion may also be obtained by the pressure of gases or by an electro-kinetic process or by an electric firing.

In summary, the principal advantages of the launching device described with respect to the existing devices are the following:

(1) Reduction of the dead weight of the engine D to be launched, thus increasing the proportion of the weight of which corresponds to the usable charge.

(2) Rapidity of the firing due to the automatic ejection ability of the launcher or at least of the launching charge as well as to the automatic reloading of the percussion and detent device which is possible.

(3) Obtention of a silent arm which is not detectable thanks to the fact that the explosion occurs in a tightly closed chamber.

(4) Obtention of a very high efficiency thanks to the very high pressures, of the order of 3000 to 10,000 kg./

cm.² realized inside the explosion chamber. It is to be noted here that this explosion chamber can support these high pressures only during a very short time interval without deformation. However, at time of the explosion, the launcher is practically completely surrounded by the percussion and detent device, as well as by the tail of the grenade D, which gives an additional security for the user.

(5) Obtention of a relatively low recoil since the part of the recoil due to the ejection of the combustion gases to the atmosphere (for example when a grenade is launched by means of a gun) is suppressed.

(6) It is possible to adapt several different gun-carriers.

(7) Any types of engines, in particular of grenades, may be launched with this launching device, such as for example anti-hail projectiles, projectiles for under-water fishing, perforating engines, compression engines, pneumatic motors, cannon projectiles and so on.

(8) Obtention of a firing distance two or three times greater for a given charge.

I claim:

1. A projectile launching device comprising a percussion device, a launcher having an explosion chamber for receiving an explosive charge, the percussion device having means for exploding a said explosive charge in the launcher, the percussion device having a cylindrical recess in its forward end, the launcher having a cylindrical outer contour at its rear end that freely but closely slidably fits in said cylindrical recess so that the side walls of said cylindrical recess encompass and outwardly confine the side walls of a portion of said explosion chamber, a piston slidable forwardly in said explosion chamber to apply the force of a said explosion to a said projectile, and means for limiting the forward motion of said piston in said chamber and for sealing the chamber against the escape of gases about said piston.

2. A device as claimed in claim 1, and a firing member mounted for reciprocation in the rear end of said launcher for detonating a said explosive charge in said chamber upon forward movement of said firing member under the impetus of said exploding means of said percussion device, said firing member having an enlarged forward end that seals the chamber against the escape of gases about the firing member upon rearward movement of the firing member under the impetus of a said explosion.

3. A device as claimed in claim 1, said explosion chamber having a portion of relatively large inside diameter and a portion of relatively small inside diameter, said piston being reciprocable in said portion of relatively large diameter, the side walls of said explosion chamber having a forwardly directed annular abutment shoulder between said portions of the explosion chamber, said abutment shoulder limiting rearward movement of said piston.

4. A device as claimed in claim 1, and a push rod extending forwardly from said piston and being slidably mounted in the forward wall of said explosion chamber for applying the force of a said explosion to a said projectile.

5. A projectile launching device comprising a percussion device, a launcher having an explosion chamber for receiving an explosive charge, the percussion device having means for exploding a said explosive charge in the launcher, the percussion device having a cylindrical recess in its forward end, the launcher having a cylindrical outer contour at its rear end that freely but closely slidably fits in said cylindrical recess so that the side walls of said cylindrical recess encompass and outwardly confine the side walls of a portion of said explosion chamber, said percussion device having a sleeve mounted for axial sliding movement thereon, a detent carried by said sleeve, means yieldably urging said detent toward a position in which it projects into the interior of the sleeve,

a member slidably disposed within the sleeve, spring means carried by the sleeve for continuously urging said slid- able member forwardly, means on said percussion device for drawing said slidable member to the rear against the action of said spring means upon forward movement of said sleeve, to a position in which said detent releasably retains said slidable member in said rearward position thereby to cock the percussion device, and means for se- lectively withdrawing said detent to permit said sliding member to spring forwardly under the impetus of said spring means to strike and actuate said exploding means.

6. A device as claimed in claim 5, said cocking device comprising a stationary rod coaxial with said sleeve, said slidable member comprising a second sleeve coaxial with said stationary rod.
